RELIEVED THREAD ROLLING DIE

Edward C. Hanna, Waynesboro, Pa., assignor to Landis Machine Company, Waynesboro, Pa., a corporation of Pennsylvania

Application May 28, 1956, Serial No. 587,855

3 Claims. (Cl. 80—6)

This invention relates to dies for rolling threads and has particular reference to an improved formation of the helical thread forming profile adjacent the edge of the die.

The dies to which the invention is especially adapted are generally cylindrical in form and are provided with a plurality of helical ridges on their circumferences, the contour of the ridges being exactly complementary to that of the thread or other helical profile to be rolled on the work piece. Where each of such ridges intersects the plane side surface of the die a partial ridge profile is formed which has the original contour on one side and a planar surface on the other. It is well known that, because of the unequal lateral force components on such partial profiles, they fracture easily in use, leading to rapid deterioration of the entire working surface of the die.

While it has been proposed to relieve such partial profiles or thread starts by grinding away a portion of the thread start adjacent the edge of the die, these relieved sections have either included a relatively widened crest, which makes penetration of the work piece difficult, or have included sharp corners in the flanks of the relieved thread forming profile.

In either case the prior known relieved profiles produce sharp corners along the flanks of the finished thread. As is well known, a sharp indentation around the circumference of a metal part reduces the tensile strength thereof quite substantially. Thus the use of either of these two profiles is precluded in the manufacture of parts specially designed for high tensile strength.

In accordance with the present invention the relieving profile of each thread start on a rolling die is formed in a manner to be described below, to minimize the effect of sharp corners in the finished thread and thus to greatly enhance the tensile strength of the product.

Furthermore, in accordance with known prior practices, the length of the relieved portion of the thread is limited to somewhat less than the circumferential extent between two adjacent thread starts, the chief reason therefor being the possibility of grinding the relief profile automatically. It has been found advantageous in certain cases to increase the length of the relieved portion in order to aid penetration of the relatively blunt relieved crest and to insure a proper termination of the thread on the work piece, particularly in case of a work piece in which the portion to be threaded is reduced in diameter with respect to the unthreaded portion. In such cases the width of the transition portion between the two diameters determines the axial extent of the relief on the die for best results and such axial extent should therefore be adaptable to the configuration of the work piece.

The relief profile of the invention has further important advantages in the case of Acme or other threads having a flat original crest instead of a sharp crest. If the flat crest is permitted to retain its original width over the relieved portion of the die, or if it is widened, the difficulty of penetrating the work piece causes a very strong bending moment to be applied thereto, deforming the

2

work piece in an undesirable manner. Narrowing and sharpening the crest profile over the radially relieved portion of the die in accordance with the present invention facilitates work penetration and minimizes the bending moment in addition to the other advantages enumerated above.

Accordingly it is an object of the invention to provide a die for cold-rolling screw threads and the like in which the thread starts at the side thereof are relieved radially with a contour designed to minimize sharp grooves in the resultant work piece.

Another object of the invention is to provide novel thread rolling dies whose individual thread ridges are gradually reduced in height toward the edge of the die, the length of the portion so relieved being variable over a wide range so as to be adaptable to work piece dimensions.

It is a further object of the invention to provide a radial relief for the thread ridges at the edge of a rolling die, said relief being designed to facilitate penetration of the work piece and to minimize the bending moment arising at the termination of the thread on the work piece.

A further object is the provision of novel thread rolling dies having their thread starts relieved in such a manner that the die is capable of producing work pieces conforming to high tensile bolt standards.

It is also an object of the invention to provide novel thread rolling dies which have extended service life and increased resistance to breakage.

Other objects and advantages of the novel dies of this invention will be apparent from the following description thereof and from the accompanying drawings, wherein:

Figure 1 is a side elevation of a thread rolling die made in accordance with the invention;

Figure 2 is a portion of the development of the periphery of the die of Figure 1;

Figure 3 is a fragmentary sectional view, on an enlarged scale, along line 3—3 of Figure 2 and showing a portion of a finished work piece in engagement with the die;

Figure 4 is a fragmentary sectional view, on an enlarged scale, along line 4—4 of Figure 2;

Figure 5 is another fragmentary sectional view on an enlarged scale, along line 5—5 of Figure 2 with the abrasive wheel used for grinding the relief shown in contact with one of the thread ridges;

Figure 6 is a fragmentary view similar to Figure 2 showing the application of the invention to a rolling die having an Acme thread; and

Figure 7 is an enlarged fragmentary section taken along line 7—7 of Figure 6 showing the original and relieved thread profile and showing the operating surface of the grinding wheel used to produce the relief in two successive positions on the rolling die.

The thread rolling die 10 shown in Figure 1 is generally cylindrical in shape and has a central opening 12 with a keyway 14 for mounting the die upon and for unitary rotation with a spindle of a thread rolling machine. Thread ridges 16 are formed on the periphery of the die 10 and as is well known in the art, these ridges are formed at the helix angle of the thread to be rolled on the work piece. This results in the formation of a plurality of continuous threads on the die, the number thereof being approximately equal to the ratio of the die pitch diameter to the work pitch diameter. In the example shown, the number of these independent and parallel threads is seven, the thread on such a die usually being referred to as a seven-start thread. It is understood that the number of starts may be varied over a wide range as desired.

In Figures 1 through 5 of the drawing, the crests of the seven thread profiles or starts are given the reference numbers 18, 20, 22, 24, 26, 28 and 30. Each start is relieved near the side 32 of the die by applying

a grinding wheel to the crest of the thread and gradually reducing the height thereof from a point of tangency 34. When the die has a thread form of the type shown in Figure 3 the crest of each thread is brought to the level of or preferably about .005" below the root line of the remainder of the die. The point 36 is the point on each start at which the start rises from its minimum height. As pointed out below the axial spacing of the point 34 from the adjacent edge of the die is based upon the specifications of the thread to be formed on the work piece. In the example shown, the point 34 is located one and one-half thread pitches axially from the side of the die. The point 36 is located one-half thread pitch from the side surface 32 of the die. From the point 36 to the point 38, at which the thread crest runs off the side of the die the thread crest is maintained at the same radius from the center of the die. This latter portion of the die, which does not operate on the work piece, is included to add strength to the die and to support the adjacent profile.

The outline of the grinding wheel 40 used to relieve the thread starts of the rolling die of Figure 1 is shown in Figure 5, in contact with the thread start 20 at a point intermediate the point of tangency 34 and a point of minimum height 36. As shown, the grinding wheel 40 is formed with a central groove 42, complementary to the profile of the relief, and with flanks 44 and 46, the latter of which is parallel to the flank of the adjacent thread start 18. As the grinding wheel 40 is fed radially toward the axis of the rolling die 10 and axially toward the end of the die, a point is reached at which the flank 46 coincides with the flank of the adjacent thread start 18 (see Figure 3). This point is the point 36 for the thread start being ground and for the remainder of its axial travel the grinding wheel is not fed radially.

The thread outline used as an example in Figures 1 through 5 of the drawings has an angle between the thread flanks of 60° and is provided with equal radii at crest and root. As shown in Figures 3, 4, and 5, the profile of the relieved portion of the thread start maintains the original radii while the angle between the thread flanks, formed by the groove 42 in the grinding wheel is substantially increased, being in this case about 120° . It will be noted that the retention of the original crest radius 48 has no deleterious effect upon the penetration characteristics of the die such as would be introduced if the relieving profile were a straight horizontal line. Also, the obtuse angle formed between the relief-profile flank and the original thread profile flank (Figure 4) is acceptable in work pieces made to high-tensile bolt standards while the sharper angle made by a horizontal truncation of the thread start is not acceptable, due to the serious reduction in tensile strength of the product caused by such sharp corners.

Due to the fact that the radius 50 on the grinding wheel 40 is carried below the root line of the original thread to a point where it is tangent to the extended flank of the adjacent thread, the distance between the center of radius 50 and the center of the crest radius 48 is smaller than the distance between the center of the crest radius 48 and the original root radius 52. Consequently, where the wheel radius 50 intersects the original root radius 52 (as in Figure 5), a corner or ridge 54 is formed which experience has shown must be minimized in order to avoid leaving undesirable markings on the finished work piece. If the angle between the flanks of the groove 42 in the grinding wheel is increased, thus increasing the distance between the centers of radii 48 and 50, the corner 54 is thus reduced. However, for good rolling and to cause the angle between the flank of the relief profile and the original thread flank to be as nearly as possible a straight line, the angle between the flanks of the groove 42 should approach as nearly as possible the angle between the original flanks of the thread, in this case 60° for best results

5 with a thread form of the type shown in Figure 3. The angle between the flanks of the groove 42 as shown in the drawing represents the best compromise between these conflicting considerations, that is, the angle between the flank of the relief profile and the original thread flank is made as large as possible consistent with the minimization of the corner 54.

10 In Figure 4 is shown an interrupted line 56—56, representing the external surface of the work blank and its relation to the rolling die profile. As shown, the work piece has a diameter 58 which corresponds approximately to the pitch diameter of the finished thread and on which the threads are to be rolled. A second and larger diameter 60 forms the body of the blank and is equal to the major diameter of the thread to be rolled. The portion of the blank having the diameter 60 commonly called the grip length is not to be penetrated by the rolling die. Between the diameters 58 and 60, the blank has a transition portion 62 whose form may 15 vary over a wide range and which is here shown as a straight-line tapered portion, the angle of taper being about 30° on one side. All of the imperfect or partial threads formed by the relieved thread starts on the die must lie between the point 64 where the line 62 intersects the major blank diameter and the point 66 where it intersects the root line 67 of the finished thread.

20 Certain standard specifications applicable to work pieces of the type shown in Figure 4 require that the thread run-out on the transition portion 62 terminate approximately $\frac{1}{4}$ of one thread pitch away from the point 64 and that the axial distance from the run-out to the point 34 where the crest is at full height be a minimum of one thread pitch and a maximum of two thread pitches.

25 30 35 These requirements dictate that the point 36 contact the work blank approximately $\frac{1}{4}$ pitch from the point 64 and that the point 34 be at least one pitch from the point 36. It has been discovered that the minimum spacing of one thread pitch best avoids the possibility of terminating the run-out at a point objectionably close to the point 64 which would necessitate scrapping the relatively expensive work pieces.

40 45 50 Figures 6 and 7 illustrate the application of a relief profile of the same general type to an Acme or worm thread. The original thread profile shown as an example in the drawings is that of a worm thread having a 20° pressure angle; that is, the angle between thread flanks is 40° . Since in this case each profile ridge 70, 72 etc. on the die 74 has a flat crest 76, greater pressure is applied to the work piece than in the case of a profile with a sharper crest. At the side edge 78 of the die 74 this pressure becomes a bending force tending to deform the axis of the work piece. This condition is alleviated by applying a radial relief to each thread start at the side of the die in the manner previously described herein.

55 60 65 70 75 As shown in Figure 7, a grinding wheel 80, inclined at the helix angle of the thread on the die and having an annular groove formed by the flanks 82 in its periphery, is applied to each individual thread ridge. The wheel 80 is shown at the middle of Figure 7 at its point of initial contact with the thread ridge 72 and this point should be the same axial distance from the side edge of the die for every thread ridge. From this position, as the grinding operation proceeds, the axis of the grinding wheel is caused to approach the axis of the die in a regular manner, following the helix of the thread until the grinding wheel runs off the side of the die is shown at the left side of Figure 7.

75 It will be seen that thus the flat crest of the ridge 72 is eliminated and the ridge gradually takes the form of the groove in the grinding wheel 80, comprising the flanks 82 with a small radius 84 joining the flanks. Therefore the terminal portion of the thread rolling ridge on the die has the radius 86 equal to radius 84 at

the crest thereof, substantially reducing the bending force acting on the work piece and facilitating penetration.

The angle between the flanks 82 is made such as to afford optimum penetration characteristics which are dependent upon the material of the work piece. In this case the wide root 88 of the thread profile on the die affords more latitude with respect to the angle between the flanks 82 and no objectionable corners such as the corner at 54 discussed above are formed so long as the width of the groove in the grinding wheel is made substantially equal to the width of the thread ridge at its root.

Also, in most cases, it is not necessary to carry the relief radially inward of the die of Figure 7 to a point at or below the level of the root of the thread starts as was done in the case of the die of Figure 1 because of the different standards which apply to work pieces having Acme threads.

The invention may be embodied in other specific forms without departure from the spirit of essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A thread rolling die of substantially cylindrical form having a plurality of thread forming ridges thereon, each ridge starting at one side of the die and extending helically around the cylindrical surface of the die to the other side thereof, each thread forming ridge having a profile constituted by a crest and side flanks, the start of each thread forming ridge being relieved so that a line

joining successive points on the apex of the crest of the start will generate a curve having its origin substantially at the root line at the side of the die and its terminus at a point of tangency with the full height of the thread ridge, the successive profiles of each start from the beginning to the full height thereof being uniform and symmetrical about a perpendicular to the crest and the crests of successive profiles being similar to the crest of the full height section of the thread forming ridge, whereby the root formed by the thread starts and the root formed by the full height thread forming ridges of the die will be substantially identical in shape and width.

2. The thread rolling die according to claim 1 wherein the crest of the relieved portion of the thread ridge is formed on a radius substantially equal to the radius of the crest of a thread ridge of full height.

3. The thread rolling die according to claim 1 wherein the angle between the flanks of the relieved portion of the thread ridge is substantially less than 180° but substantially greater than the angle included between the flanks of a thread ridge of full height.
